UNITED STATES PATENT OFFICE.

HUGO HOHENSTEIN, OF NEW YORK, N. Y.

DESIGN FOR A LAMP-SHADE.

SPECIFICATION forming part of Design No. 21,702, dated July 12, 1892.

Application filed May 27, 1892. Serial No. 434,674. Term of patent 3½ years.

To all whom it may concern:

Be it known that I, HUGO HOHENSTEIN, a citizen of the United States, and a resident of the city of New York, in the county of New 5 York and State of New York, have invented a new Design for Lamp-Shades, of which the following is a specification.

In the accompanying drawing a perspective view of a lamp-shade, showing my new design, is given.

The leading feature of my design consists of a fluted shade having a top part in the shape of a truncated cone and a bottom part also in the shape of a truncated cone and a 15 drapery along the edge of the bottom part, the inclination of the sides of the truncated cone forming the top part being much greater than the inclination of the sides of the truncated cone forming the bottom part, so that 20 an obtuse angle is formed at the junction of said two parts.

A is the top part of the fluted shade, made in the shape of a truncated cone. B is the bottom part of the shade, also made in the shape of a truncated cone, but of considerably less inclination than the top cone A, whereby an obtuse-angle offset is formed at the base of the upper truncated cone and at the top of the lower truncated cone, and C is the drapery along the bottom edge of the shade. 25

What I claim is—

The design for a lamp-shade, substantially as herein shown and described.

In testimony that I claim the foregoing as my invention I have signed my name in presence of two subscribing witnesses. 35

HUGO HOHENSTEIN.
